(57) **CLAIM**

The ornamental design for a door lock, as shown and described.

DESCRIPTION

FIG. 1 is a top perspective view of embodiment 1 of a door lock showing my new design;

FIG. 2 is a bottom perspective view of embodiment 1 thereof;

FIG. 3 is a front view of embodiment 1 thereof;

FIG. 4 is a rear view of embodiment 1 thereof;

FIG. 5 is a left side view of embodiment 1 thereof;

FIG. 6 is a right side view of embodiment 1 thereof;

FIG. 7 is a top view of embodiment 1 thereof;

FIG. 8 is a bottom view of embodiment 1 thereof;

FIG. 9 is a top perspective view of embodiment 2 of a door lock showing my new design;

FIG. 10 is a bottom perspective view of embodiment 2 thereof;

FIG. 11 is a front view of embodiment 2 thereof;

FIG. 12 is a rear view of embodiment 2 thereof;

FIG. 13 is a left side view of embodiment 2 thereof;

FIG. 14 is a right side view of embodiment 2 thereof;

FIG. 15 is a top view of embodiment 2 thereof; and,

FIG. 16 is a bottom view of embodiment 2 thereof.

The broken lines in the drawings illustrate the portions of the door lock, which form no part of the claimed design.

1 Claim, 16 Drawing Sheets
